UNITED STATES PATENT OFFICE.

HENRY D. MURDOCK, OF WILKINSBURG, PENNSYLVANIA, ASSIGNOR TO WESTINGHOUSE ELECTRIC & MANUFACTURING COMPANY, A CORPORATION OF PENNSYLVANIA.

TRANSFORMER RADIATOR VALVE.

Application filed May 11, 1921. Serial No. 468,720.

My invention relates to transformers and to other fluid-cooled apparatus having detachable radiator elements employed in connection therewith, and it has particular relation to valves adapted to be utilized to close the communication between the main tank and the radiators to facilitate the removal of the latter for the purpose of replacement or repairs.

10 Heretofore, in certain types of apparatus, and particularly in large transformers employing detachable radiator elements, considerable difficulty and inconvenience were encountered when it became necessary to remove a radiator element for any purpose, such as to repair leaks, by reason of the fact that it was necessary to first entirely empty the main tank and all of the communicating radiators of the fluid contained

20 therein.

This removal of the oil or other fluid necessitated the utilization of a large number of barrels or other containers and usually resulted in the loss of a considerable quantity of oil.

One of the objects of my invention is to provide a valve which is particularly adapted to close the communication between the main tank and the radiator elements, thereby rendering it unnecessary to remove the fluid contents of the tank and other radiators when one of the radiators is removed for the purpose of repairs.

Another object of the invention is to provide a valve of compact construction that may be installed in connection with transformers of standard types and by employing relatively few connecting joints.

40 A further object of my invention is to provide a device of the class described that may be quickly and easily operated and that may be manufactured at a relatively small cost.

The single figure of the accompanying drawings is a vertical longitudinal sectional view through a portion of a transformer tank and radiator connections, the radiator element being shown in elevation.

Referring to the drawings, 1 indicates 50 a portion of a transformer tank comprising a cylindrical side wall 2 a top 3, and a bottom 4. A radiator element, illustrated as comprising a plurality of spaced and parallel vertically-extending envelopes 5 connected at the upper and lower extremities

thereof by means of header members 6, is suitably mounted exteriorly of the tank 1 for communication therewith.

Inasmuch as the construction of the upper and the lower communicating means are 60 substantially similar, a description of one of them will be sufficient.

The header members 6 are preferably connected to the main tank 1 of the transformer for communication therewith by means of 65 elbow members 7, each of which has an outwardly-extending flange 8 at its end adjacent to the tank. The flange 8 is preferably clamped, by bolts 9, to a coupling member 10 which is suitably secured to a relatively short tubular section 11 carried by the tank.

The member 10 is provided with an interiorly screw threaded aperture 12 into which is screwed a valve seat 13 which extends within the tubular member 11, and in spaced relation therewith. The valve seat 13 is preferably interiorly screw threaded, as at 14, to engage a similar screw-threaded valve member 15. The seat 13 is further provided with a plurality of side apertures 16 adjacent to the inner end thereof which constitute means of communication between the member 11 and the radiator.

An operating rod or handle 17 removably engages the valve 15 and extends through the elbow 7 and out through a screw-threaded nipple 18. A cap 19, provided with a suitable packing 20, is provided for the nipple 18 and entirely encloses the end of the rod 17 when the rod occupies its innermost position, thus preventing leakage at the point where the rod merges from the elbow 7.

An aperture or port 21 which constitutes a means for draining the radiator prior to detaching the same is normally closed by means of a screw threaded plug 22.

When the radiators are secured in position with respect to the tank, under normal operating conditions, the valves 15 are moved to their innermost positions, as illustrated in the upper portion of the drawing. In this position, the fluid contained in the tank 1 may pass freely through the apertures 16 in the valve seat 13 and through the elbow 7 into the radiator element for free circulation therethrough. If it is desired, however, to detach the radiator for any purpose, the caps 19 are removed to

provide access to the rods 17. The rods 17 are then so manipulated as to screw the valve members 15 outwardly into the positions illustrated in the lower portion of the drawing, in which positions communication between the main tank and the radiator through the parts 16 is interrupted.

The plugs 22 at the upper and the lower portions of the radiator are then removed, 10 allowing the oil or other fluid to be drained from the radiator through the lower aperture and, at the same time, permitting air to enter through the upper aperture. The bolts 9 may then be removed and the radiator element detached from the transformer tank. When the radiator is detached from the tank, the rods 17 are supported within the elbows 7 by means of the nipple 18 and a suitable spider or guide 23.

20 From the foregoing description, it will be apparent that the necessity of providing a large number of containers for the reception of the contents of the transformer tank and radiators is obviated, as it is only necessary 25 to provide a relatively small container for the fluid contents of the radiator that is to be detached.

What I claim as my invention is:

1. A transformer tank having a detachable radiator element mounted thereon, tubular coupling members disposed between said tank and said radiator to establish communication therebetween at the upper and lower portions thereof, valve seats disposed within said coupling members each provided with ports through which communication is established between said tubular members and said radiator, a valve co-operating with each of said valve seats and adapted to interrupt the communication through said ports and means for actuating said valve.

2. A transformer tank having a detachable radiator element mounted thereon, 45 tubular coupling members disposed between

said tank and said radiator to establish communication therebetween at the upper and lower portions thereof, valve seats facing said tank, disposed within said coupling members and provided with ports through 50 which communication is established between said tubular members and said radiator, a valve co-operating with each of said valve seats and adapted to interrupt the communication through said ports, and means for 55 actuating the valves.

3. A transformer tank having a detachable radiator element mounted thereon, tubular coupling members disposed between said tank and said radiator to establish communication therebetween at the upper and lower portions thereof, valve seats facing 60 said tank, disposed within said coupling members and provided with ports through which communication is established between 65 said tubular members and said radiator, a valve co-operating with each of said valve seats and adapted to be moved outwardly from said tank into the valve seats to interrupt the communication through said 70 ports, and means for actuating the valves.

4. A transformer tank having a detachable radiator element mounted thereon, tubular coupling members disposed between said tank and said radiator to establish communication therebetween at the upper and lower portions thereof, valve seats facing inwardly relative to said tank, disposed within 75 said coupling members through which communication is established between said tubular members and said radiator, a valve co-operating with each of said valve seats and adapted to be moved outwardly relative 80 so said tank into the valve seats to interrupt communication between the tank and the 85 radiator, and means for actuating the valves.

In testimony whereof, I have hereunto subscribed my name this 29th day of April, 1921.

HENRY D. MURDOCK.
